(57) CLAIM

The ornamental design for an electrical connector, as shown and described.

DESCRIPTION

FIG. 1 is a bottom plan view of an electrical connector showing an embodiment of our new design;

FIG. 2 is a side elevational view thereof, the opposite side being a mirror image;

FIG. 3 is a top plan view thereof;

FIG. 4 is a front elevational view thereof; and,

FIG. 5 is a rear elevational view thereof.
